UNITED STATES PATENT OFFICE.

DAVID T. WELCH, OF ST. LOUIS, MISSOURI.

IMPROVEMENT IN LIFTING-JACKS.

Specification forming part of Letters Patent No. **157,254**, dated November 24, 1874; application filed October 20, 1874.

To all whom it may concern:

Be it known that I, DAVID T. WELCH, of St. Louis, in the State of Missouri, have invented an Improved Screw-Jack for Lifting or Applying Pressure; and I do hereby declare the following to be a full and correct description of the same, reference being had to the accompanying drawings, in which—

Figure 1 is a side elevation, partly in section, of my machine. Fig. 2 is a horizontal section on line $x-x$ of Fig. 1.

The same letter indicates the same part in both figures.

My invention consists in the construction, substantially as hereinafter described, of a machine or instrument for the more convenient application of the power of the screw, either for raising weights or for effecting compression in either direction.

The drawing represents a machine embodying the principle of my invention, applicable to the handling of railroad-iron, to the lifting of heavy weights, and to the production of powerful upward pressure.

In the drawing, A A mark the feet of the machine, which support two uprights, B B, united at top by a cross-beam, C. These together form a gallows of convenient shape for straddling the work. A large screw, S, passes down through an opening in the middle of the cross-beam C. Upon it is a large nut, N, held in position by the yoke-beam D, as shown in Fig. 1. The nut is circular in shape, as seen in Fig. 2, and has cut upon its perimeter a thread to receive and engage the threads of a worm, W, on the horizontal shaft F. The journals of this shaft turn in boxes in the ends of the arms E E. They project beyond the ends of the frame, and either or both may have a crank, K, attached, by which the shaft F can be rotated. Swiveling on the top of the screw S is a platen, H, intended for use when

the machine is employed as a press. On the lower end of the screw is a swivel, to which is affixed a grapnel for holding the weight to be lifted. (In this case shown as a railroad-rail.) Above the screw-thread a hand-wheel, G, is fixed to the screw S, by which the screw may be rotated.

The operation is as follows: The machine being placed astraddle of the work, the weight to be lifted is grasped by the grapnel. The hand-wheel G is then operated, turning the screw S in the direction to raise it. When the strain becomes too heavy to be raised by the hand-wheel, the crank K is called into use, turning the worm W and the nut N. The weight not being allowed to rotate, the turning of the nut in the proper direction will raise the screw S and the weight attached to it.

By proper graduation of the pitch of the worm, nut, and screw-threads, and of the length of the crank-arm, any desired multiplication of the applied power can be effected.

It is obvious that, by the same arrangement of mechanism, a press of great power can be produced by the addition of the necessary platens.

Having thus described my invention, what I claim, and desire to secure by Letters Patent, is—

The combination of the uprights B B, cross-beam C, and yoke-beam D with the crank K, shaft F, worm W, nut N, and screw S, provided with a swivel and grapnel, all constructed substantially as and for the purpose set forth.

The above specification of my said invention signed and witnessed at St. Louis this 23d day of September, A. D. 1874.

DAVID T. WELCH.
